UNITED STATES PATENT OFFICE.

GEORGES DUNAIME, OF PARIS, FRANCE, ASSIGNOR TO CHERAMY, INC., OF NEW YORK.
N. Y., A CORPORATION OF NEW YORK.

DESIGN FOR A BOTTLE.

Application filed June 1, 1927. Serial No. 22,287. Term of patent 7 years.

To all whom it may concern:

Be it known that I, GEORGES DUNAIME, a citizen of France, residing at 47 R. Popincourt, Paris, France, have invented a new, original, and ornamental Design for a Bottle, of which the following is a specification, reference being had to the accompanying drawing, forming a part thereof.

In the drawing,

Fig. 1 is a front elevation of a bottle showing my design.

Fig. 2 is a side elevation.

Fig. 3 is a plan view of the bottle showing my new and ornamental design.

I claim:

The ornamental design for a bottle as shown.

GEORGES DUNAIME.
